(57) **CLAIM**

The ornamental design for a flow cytometer, as shown and described.

DESCRIPTION

FIG. 1 is a top, front and right side perspective view of the flow cytometer;

FIG. 2 is a top, front and left side perspective view of the flow cytometer;

FIG. 3 is a top, rear and right side perspective view of the flow cytometer;

FIG. 4 is a top, rear and left side perspective view of the flow cytometer;

FIG. 5 is a front view of the flow cytometer;

FIG. 6 is a rear view of the flow cytometer;

FIG. 7 is a right side view of the flow cytometer;

FIG. 8 is a left side view of the flow cytometer;

FIG. 9 is a top view of the flow cytometer; and,

FIG. 10 is a bottom view of the flow cytometer.

The broken lines in the drawings illustrate portions of the flow cytometer which form no part of the claimed design. The dash-dot-dash broken lines illustrate the boundaries of the claimed design and form no part thereof.
